UNITED STATES PATENT OFFICE

2,464,774

SINGLE ROLL CRUSHER WITH OPPOSED
TOOTHED-APRON FEEDEdwin H. Keiper, Philadelphia, Pa., assignor to
Pennsylvania Crusher Company, Philadelphia,
Pa., a corporation of New York

Application April 22, 1946, Serial No. 664,057

3 Claims. (Cl. 241—187)

1

This invention relates to roll crushers, and particularly to such crushers for handling wet and sticky materials.

The object of the invention is to provide a feeding and crushing action which will carry the material effectively through the crushing zone and cooperate with the roll to attain reduction of the material to desired size.

Further objects of the invention particularly in the form and mounting of the traveling breaker plate will appear from the following description taken in connection with the accompanying drawings in which

Fig. 1 is a vertical sectional view through the machine;

Fig. 2 is a plan view on reduced scale of the machine shown in Fig. 1; and

Fig. 3 is a partial vertical sectional view of a modified form.

In the accompanying drawings the roll crusher frame comprises side pieces 9, base plate 10 and end piece 11, the hopper 12 being mounted as shown on the frame having a slanting end portion coinciding in direction with the cross piece 13 and delivering material through the opening between the cross piece and the edge 14 of the opposite member of the hopper.

A roll crusher shaft 15 mounted in bearings in the side pieces 9 carries the crusher roll 16 having teeth 17, 18, and the crushed material is discharged downward through the opening in the base plate 10 and the outlet 19.

A traveling breaker plate structure 20 composed of a continuous chain having link members 21 with teeth 22 is positioned as shown to approach the periphery of the crusher roll at an angle across the feed of the material from the hopper 12, the crusher roll rotating clockwise as indicated and the breaker plate sections moving downward adjacent the roll. The breaker plate chain travels around the lower or pulling sprocket 24 on shaft 25 and around the upper sprocket on shaft 36 within the cover piece 35 mounted on the frame 9, 11. The drive for the sprocket shaft 25 (Fig. 1) is by chain 26 from speed change mechanism 27 driven in turn by chain 28 from the countershaft 29 driven by a belt 30 from the motor 31. Countershaft 29 has its opposite end as the drive pinion 32 driving the gear 33 of the crusher roll shaft 15.

A slide plate 40 mounted by its ribs 41 on cross shafts 42 between the side plates 9 supports the breaker plate chain as it moves downward with the material toward the crusher roll. This traveling breaker plate or apron moving down-

2

ward with a lineal speed of 3' to 4' per minute, for instance, forms a retaining movable wall for the material, constantly tending to drag the material down between the roll crusher teeth and the apron moving in the same direction at a lesser speed to the crushing area. Here the teeth of the roll and the teeth of the apron cooperate to break the material, the major teeth 18 of the crusher preferably having their tips moving in the grooves separating the teeth 22 of the chain or apron.

In this manner the bottom and the side of the chamber receiving the material from the hopper 12 both move downward in the same direction along converging lines to drag the material in between them, this combination being particularly effective in handling wet and sticky materials and avoiding any arching over or packing of these materials. The discharge opening 13, 14 of the hopper 12 is large and directed downward at an angle, and the traveling apron 20 proceeds downward from the top point well above the lower lip 13 of the hopper and substantially on a level with the upper edge 14 of the hopper opening.

This combination of the hopper formation and the cooperating traveling surface of the roll and apron will take bauxite and other similar plastic or wet materials and subject them to effective reduction from relatively large pieces, 24 to 30" to smaller fragments such as 1 to 1 1/2", the exact reduction depending, of course, upon the hardness and size of the entering pieces of the material.

In Fig. 3 a modification is shown mounting the apron chain 20 on an upper sprocket 47 of shaft 46 which may be driven, and carrying the lower portion of the chain around an auxiliary endless roller link belt running around the lower cylinder 50 on shaft 48, and the upper cylinder roller 52 on shaft 51 between the sides 9 of the frame. The shaft 48 is preferably driven as by a chain running on sprocket at the end of the shaft. Slide plates 55 joined by web members 56 are mounted on cross bars 57 between the frame sides 45 9 and the crushing thrust against the apron is transmitted from the apron links 21 to the rollers 53 and thence to the slide plates 55 so that these rollers 53 join together in endless chain formation by links 54 and move downward with the chain 20 at about one-half the speed of the chain and form an intermediate roller support between the chain and the slide plate 55 reducing the frictional resistance between the apron and the plate.

The wide hopper opening provides an extensive

feed of the material to the moving surfaces of the roll and apron so as to avoid any constrictions or bottle-necks, and in effect submitting the entire mass of the hopper feed to the action of the moving surfaces so that the material is compelled to follow down into the grip of the crusher action between the roll and the apron.

I claim:

1. In a roll crusher the combination with a roll turning in a predetermined direction, of a feed hopper vertically above the center of said roll and comprising an inclined end surface terminating at one side of the top of the roll and discharging material from the hopper onto the top part of the roll periphery, and endless series of links providing a sliding apron at the opposite side of said hopper receiving material therefrom and extending downward at the other side of said roll from substantially above the top of the roll to the level of the center thereof so that the entire mass of the hopper feed is engaged by the moving surfaces of the roll on one side and the sliding apron on the other and is drawn into the grip of the crusher action between the roll and the apron as they come together, cooperating teeth on said roll and said apron, means for driving said roll and said apron at predetermined relative speeds to draw in and crush said material between them.

2. In a roll crusher the combination with a roll turning in a predetermined direction, of a feed hopper vertically above the center of said roll and comprising an inclined end surface terminating at one side of the top of the roll and discharging material from the hopper onto the top part of the roll periphery, a substantially vertical wall for said feed hopper opposite the upper portion of said inclined end surface, an endless series

of links providing a sliding apron at the opposite side of said hopper receiving material therefrom and inclined downward from adjacent the lower end of said vertical wall to adjacent the vertical periphery of the roll at the side of said hopper opposite to said inclined end surface, said apron receiving material from said hopper and moving it downward toward said roll so that the entire mass of the hopper feed is engaged by the moving surfaces of the roll on one side and the sliding apron on the other and drawn into the grip of the crusher action between the roll and the apron as they come together, cooperating teeth on said roll and said apron, means for driving said roll and apron at predetermined relative speeds to draw in and crush said material between them, and a free discharge for the material passing from said roll and apron.

3. A roll crusher as set forth in claim 1 in which the means for driving the roll and apron comprises a speed change mechanism reducing the rate of lineal movement of the apron to less than that of the roll periphery.
